Inventor
Benjamin Brenner

By Thomas A. Jenkins Jr.
Attorney

UNITED STATES PATENT OFFICE.

BENJAMIN BRENNER, OF PROVIDENCE, RHODE ISLAND.

VANITY CASE.

Application filed January 15, 1923. Serial No. 612,769.

To all whom it may concern:

Be it known that I, BENJAMIN BRENNER, a citizen of the United States, residing at Providence, in the county of Providence, 5 and State of Rhode Island, have invented certain new and useful Improvements in Vanity Cases, of which the following is a specification.

My invention relates to improvements in vanity boxes, of the class adapted to contain both powder and rouge.

One object of my invention is to provide a small and compact powder and rouge container, no larger than a powder box of small 15 size and small enough to readily fit into a lady's pocket book or mesh bag, yet due to the telescoping features of the box, able to contain a rouge compact, and a combined mirror and partition member revolvably 20 mounted therein, in addition to the powder compact.

A further object of my invention is to provide in one element a combined mirror and partition member, adapted to retain the 25 rouge pad in position when the powder is being used, and at the same time providing suitable reflecting means for the use thereof, and adapted to retain the powder pad in 30 position when the rouge is being used, at the same time providing suitable reflecting means for the use thereof.

A further object of my invention is to provide a vanity box wherein both the powder and the rouge are readily accessible.

A further object of my invention is to provide by means of a single mirror revolvably mounted between the powder and rouge compacts a reflecting means readily available for use as desired either with the 40 powder or the rouge.

These and such other objects of my invention as may hereinafter appear, will best be understood by the description of one embodiment thereof, such as is shown in the 45 accompanying drawings.

In the drawings, Fig. 1 is a perspective view of my vanity box in open position, with the mirror partially tilted.

Fig. 2 is a cross section through the centre 50 of the box.

Fig. 3 is a sectional view, showing in detail how the bail member, the body member and the cover are hingedly connected together.

Fig. 4 is a detailed view of the hinge used.

In the drawings, wherein like characters of reference indicate like parts throughout, 1 is the main body member of my device, normally stamped out of suitable material, adapted to contain the powder which is preferably in the form of a compact 2. 3 is the cover member. In practice, more powder is used by the average woman than rouge, and at the same time it is desirable to construct just as small a box as possible, so that it may 60 conveniently fit in a lady's pocket book or mesh bag. Bearing these ends in view, I provide, usually by means of stamping, a central circular recess 4 in the cover member 3, large enough to contain the desired 65 amount of rouge which is preferably in the form of a compact 5. Any convenient type of hinge means may be used for connecting the cover and body members. In the construction shown, I provide the hinge-plates 70 6 and 7, adapted to be attached to the body and cover members 1 and 3, respectively. The hinge-plates 6 and 7 are provided at their ends with rounded projections 8 which are placed in holes 9 cut in the body and 75 cover members 1 and 3 respectively, and are bent over as shown at 8a in Fig. 1 to fasten the hinge-plates 6 and 7 thereto. The projections 10 extending from the hinge-plates are bent over as usual to form the circular 80 bearings 11 for the registration of the hinge-pin 12 therein. I mount a bail member 14 on said hinge means between the body member 1 and the cover member 3 as follows:

To the central portion of the bail member 90 14, I attach the mount 15, the lower end 16 of which is bent over to form a circular bearing for the registration of the hinge-pin 12 therein. It is thus obvious that the main body member 1, the cover 3, and the bail 95 member 14, are pivotally connected by means of the hinge-pin 12. The outer ends 17 of the bail member are provided with inwardly extending lugs 18. I provide a combined 100 mirror and partition member 20, preferably stamped out of suitable material, and with a single mirror 21, suitably attached or bevelled to one side thereof. At diametrically opposite points on the outer periphery of said combined mirror and partition member 20, I provide the holes 22, which are adapted to receive the lugs 18, projecting inwardly from the bail member 14, and thus 105 revolvably mount the combined mirror and partition member 20 thereon. At convenient 110

points in the outer periphery of the combined mirror and partition member 20, I provide the lugs 23 and 23^a, the lug 23 adapted to register in a recess 24, provided in the bail member 14, to retain said mirror and partition member 20 in position, so as to provide suitable reflecting means when it is desired to use the powder. When it is desired to use the rouge, it is merely necessary to turn the combined mirror and partition member 20 half way round, when the lug 23^a will register in the recess 24, and enable the combined mirror and partition member 20 to provide suitable reflecting means for the use of the rouge. Between the powder compact 2 and the combined mirror and partition member 20, I provide the removable powder pad 26, and between the rouge compact 5 and the combined mirror and partition member 20, I provide the removable rouge pad 27, usually of a diameter equal to that of the annular recess 4. The main body member 1, is provided with an inwardly offset circular vertical flange portion 28, which is adapted to telescope into the flange of the cover 3, when the said cover 3 and main body member 1 are closed together. It is thus obvious that when my vanity box is closed, the combined mirror and partition member 20, and the powder and rouge pad 26 and 27, are retained between the body and cover members 1 and 3, in compact relation thereto. To retain the body and cover members 1 and 3 in closed position, I provide the body member 1 with a lug 30 adapted to register in the recess 31, in the cover 3.

To use the powder, throw open the cover member 3, lift up the bail member 14, and revolve the combined mirror and partition member 20 until the lug 23 catches in the recess 24, throw back the bail member 14 on the cover member 3. It is obvious that the powder is then available for use, and that the mirror 21 will now provide suitable reflecting means for the use thereof, and that the combined mirror and partition member 20 lying against the cover 3 will retain the rouge 4, and rouge pad 27, in position. By varying the length of the opening arc of the cover 3, the mirror 21 may be adjusted for the most advantageous use thereof. While the box is still open, to use the rouge, lift up the bail member 14, revolve the combined mirror and partition member 20 until the lug 23^a catches in the recess 24, throw over the bail member 14 on the body member 1, turn the vanity box around, and by again varying the length of the opening arc, once again adjust the mirror for the most advantageous use thereof in connection with the rouge. The combined mirror and partition member 20, will rest against the body 1, and retain the powder 2, and powder pad 26 in position. When through using, close the

box, and the lug 30, registering in the recess 31, will retain the body member and cover 3 in closed position.

It is understood that the invention is not limited to the specific embodiment shown, and that various deviations may be made therefrom without departing from the spirit and scope of the appended claims.

What I claim as new and desire to secure as Letters Patent is:

1. A vanity box, comprising a main body member, a cover member, having a central circular internal recess therein of smaller diameter than the cover projecting externally above the plane of the cover, hinge means pivotally connecting said body and cover members, a bail member pivotally connected to said hinge means between said body and cover members, a combined mirror and partition member revolvably mounted on said bail member, means to lock said combined mirror and partition member in operative position on said bail member, a quantity of powder in the body member, a quantity of rouge in the annular recess in the cover member, pads between the powder and rouge and the combined mirror and partition member, said body member having an inwardly offset vertical flange portion adapted to telescope into the flange of the cover when the said members are closed together, and to contain there between in compact relation to the cover and body members, the pads and the combined mirror and partition member, and means to lock said body and cover members in closed position.

2. A vanity box, comprising a main body member, a cover member, having a central circular internal recess therein of smaller diameter than the cover projecting externally above the plane of the cover, hinge means pivotally connecting said body and cover members, a bail member pivotally connected to said hinge means between said body and cover members, a partition member revolvably mounted on said bail member, a mirror attached to one side thereof, lugs on said partition member adapted to register in a recess on said bail member to retain said partition member in operative position, a quantity of powder in the body member, a quantity of rouge in the annular recess in the cover member, pads between the powder and rouge and the partition member, said body member having an inwardly offset vertical flange portion adapted to telescope into the flange of the cover when the said members are closed together, and to retain there between in compact relation to the cover and body members, the pads and the partition member, and a lug on said cover adapted to register in a recess in said body to retain the cover in closed position.

3. A vanity box, comprising a main body member, a cover member, having a central

circular internal recess therein of smaller diameter than the cover projecting externally above the plane of the cover, hinge means pivotally connecting said body and cover members, a bail member pivotally connected to said hinge means between said body and cover members, a combined mirror and partition member revolvably mounted on said bail member, a quantity of powder in the body member, a quantity of rouge in the annular recess in the cover member, pads between the powder and rouge and the combined mirror and partition member, said body member having an inwardly offset vertical flange portion adapted to telescope into the flange of the cover when the said members are closed together, and to contain there between in compact relation to the cover and body members, the pads and the combined mirror and partition member.

4. A vanity box, comprising a main body member, a cover member, having a central circular internal recess therein of smaller diameter than the cover projecting externally above the plane of the cover, hinge means pivotally connecting said body and cover members, a bail member pivotally connected to said hinge means between said body and cover members, a combined mirror and partition member revolvably mounted on said bail member, a quantity of powder in the body member, a quantity of rouge in the annular recess in the cover member, and pads between the powder and rouge and the combined mirror and partition member.

5. A vanity box, comprising a body member adapted to receive a powder compact, a cover member hingedly connected thereto, provided with a circular internal recess of smaller diameter than the cover projecting externally above the plane of the cover adapted to receive a rouge compact, said body member having an internally offset vertical flange portion adapted to telescope into the flange of the cover when the said members are closed together, a combined mirror and partition member revolvably hinged to said body and said cover members adapted to separate the powder and rouge and to extend within said body and cover members when the latter are closed together.

55 6. A vanity box, comprising a body mem-

ber, adapted to receive a powder compact, a cover member hingedly connected thereto, provided with a circular internal recess of smaller diameter than the cover projecting externally above the plane of the cover adapted to receive a rouge compact, a combined mirror and partition member revolvably hinged to said body and said cover members adapted to separate the powder and rouge, and pads between the powder and rouge and said combined mirror and partition member.

7. In vanity boxes, an external cover member provided with a central circular recess of smaller diameter than the cover projecting externally a short distance above the outer flat surface of the cover adapted to receive a rouge compact.

8. In vanity boxes, an external cover member provided with a recess of smaller diameter than the cover projecting externally a short distance above the outer flat surface of the cover.

9. A vanity box, comprising a body member adapted to receive a powder compact, a cover member hingedly connected thereto, provided with a circular internal recess of smaller diameter than the cover projecting externally a short distance above the outer flat surface of the cover adapted to receive a rouge compact, said body portion having an internally offset vertical flange portion adapted to telescope into the flange of the cover when the said members are closed together, and a combined mirror and partition member carried by said body and cover members adapted to separate the powder and rouge and to extend within said body and cover members when the latter are closed together.

10. A vanity box, comprising a body member adapted to receive a powder compact, a cover member hingedly connected thereto provided with a circular internal recess of smaller diameter than the cover projecting externally a short distance above the outer flat surface of the cover adapted to receive a rouge compact, and a combined mirror and partition member carried by said body and cover members adapted to separate the powder and rouge.

In testimony whereof I affix my signature.

BENJAMIN BRENNER.
